F. C. VARTULI.
COMBINATION LOCK.
APPLICATION FILED MAY 22, 1920.

1,352,771.

Patented Sept. 14, 1920.

By E. C. Vrooman and Co,
his Attorneys.

UNITED STATES PATENT OFFICE.

FRANCIS C. VARTULLI, OF WINOOSKI, VERMONT.

COMBINATION-LOCK.

1,352,771.

Specification of Letters Patent. Patented Sept. 14, 1920.

Application filed May 22, 1920. Serial No. 383,423.

To all whom it may concern:

Be it known that I, FRANCIS C. VARTULLI, citizen of the United States, residing at the village of Winooski, in the town of Colchester, in the county of Chittenden and State of Vermont, have invented certain new and useful Improvements in Combination-Locks, of which the following is a specification, reference being had therein to the accompanying drawings.

This invention relates to a combination lock, and has for its object the production of a comparatively simple and efficient lock that can be easily operated when one knows the combination, and which is durable in structure and relatively inexpensive to manufacture.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a front view in elevation of my lock, while

Fig. 2 is a side view of the same.

Fig. 3 is a view, looking at the inside of the casing with the shackle removed.

Fig. 4 is a sectional view taken on line 4—4, Fig. 3, and looking in the direction of the arrows.

Fig. 5 is a view in elevation of the shackle, while

Fig. 6 is a side view of the same.

Fig. 7 is a view in elevation of the shackle, looking at the opposite face to that shown in Fig. 5.

Fig. 8 is an inside view of the front plate of the casing, showing the inner ends of the knob devices.

Fig. 9 is a section, taken on line 9—9, Fig. 8, and looking in the direction of the arrows.

Fig. 10 is a view of a modified form of my lock, showing particularly the inner face of the front plate of the casing.

Fig. 11 is a sectional view, taken on line 11—11, Fig. 10, and looking in the direction of the arrows.

Fig. 12 is a perspective view of the knob

device of the embodiment shown in Figs. 10 and 11.

Fig. 13 is a perspective view of one of the 55 dogs.

Fig. 14 is a sectional view of the auxiliary knob device.

Referring to the drawings by numerals, 1 designates the casing against which is 60 placed the front plate 2. The casing 1 and the plate 2 are fastened together by any suitable means, as rivets 3.

On one side of the casing is a lug 4 having an aperture 5, in which aperture 5 may 65 be placed a retaining chain, for fastening the lock to a suitable support, whereby it will not be displaced or lost. In the inner face of the casing 1 are elongated pockets 6 that register with dogs 7 carried by the 70 sliding shackle 8. The shackle 8 is provided with a hook 9 at its outer end, and is provided with a cut-out portion 10 on one side, producing a shoulder, at 11, that strikes against the inner end 13 of the lug 14 75 formed in the casing 1, for preventing the shackle from being entirely removed from the casing. A bent or angle spring 15, secured in any suitable manner to the casing 1, as at 16, presses against the lower end of 80 the shackle for normally forcing the shackle outward. The spring is cut-away, as at 17, Fig. 4, to allow the spring to pass the inner end of the knob devices, as the shackle moves outwardly when the dogs are released from the knob devices.

Each dog 7 comprises a body 18 that has, at its lower end, oppositely-extending arms 19, which arms 19 fit in suitable recesses 20 (Fig. 7) formed at opposite sides of the 90 elongated apertures 21, through which apertures the bodies 18 of the dog devices extend (Figs. 6 and 7). By the arms 19 being seated in the recesses 20, the dogs are pivotally mounted upon the shackle and are 95 adapted to be engaged by the inner ends of the knob devices 22. The upper or outer end of the body 18 of each dog device is provided with a tooth 23 that passes through the smaller slots 24 formed on the rim 25 at the inner end of each knob device, but when the combination has been solved by the operator of the knob devices, the large slots 26 (Fig. 8) will be in parallelism 100

or opening nearest to the open end of the casing 1, thereby permitting the entire bodies 18 of the dogs to slide through the rims at the inner ends of the knob devices, 5 permitting the shackle to move to its outer or open position upon the casing.

Washers 27 are seated in the plate 1 for securing the knob devices 22 in a rotatable assembled position upon the plate. Each 10 knob device is provided on its outer face with suitable letters, or other designating means, to indicate a combination that must be solved or "worked" before the enlarged slots 26 are in the position shown in Fig. 8 15 for releasing the dogs from the knob devices, and permitting the shackle to move through the action of spring 15, to its open or outer position. To cause the dogs to extend outwardly, at their upper or outer 20 ends, bent or angle springs 28 are provided, each spring including a comparatively long arm pressing against the back of the dog body 18, the spring being fastened at its base by having the edges of shackle recess 25 hammered or turned down over the spring, and while the shackle is in place within the casing, the springs 28 will be retained in an accurate, operative position for holding the dogs out and in correct position to enter the 30 rim 25 of the knob devices.

In the embodiment shown in Figs. 10 and 12, I employ only one knob device 29, which knob device is provided at its inner end with a rim 25, like the other knob devices in Figs. 35 1 to 9. Around the rim 25 is loosely mounted a ring 30, which ring is retained upon the rim 25 by means of a two-fingered spring 31; this spring 31 is seated in a groove 32 (Fig. 11), to keep it in place on the ring 30, and 40 the spring acts as a brake or retarding means, preventing the ring from too readily rotating upon the rim 25. The ring 30 is provided with two shoulders 33 formed upon opposite sides of the large opening 26 of the 45 ring, corresponding to the same large opening in the rim 25 (Fig. 10), so that when the enlarged opening 26 in both the rim 25 and the ring 30 register, the single dog device that may be carried by the shackle 9, will 50 pass through and release the shackle. On the rim 25 is formed a bent-over portion or lug 34 which, upon rotating the knob device 29, will slide over a portion of the inner face of the ring 30, until the lug engages one of 55 the shoulders 33, whereupon the ring 30 will be rotated with the knob device for causing the same to be moved to the position shown in Fig. 10, for allowing the shackle with the single dog device, like the dog devices shown 60 in Figs. 1 to 7, to pass therethrough. It will be obvious that upon continuing the rotation of the knob device 29, after the lug 34 has engaged a shoulder, the ring 30 will be moved to such a position as to place the large 65 slot 26 to one side of the position shown in

Fig. 10, when the knob device will have been so placed as to prevent the end of the dog body from passing out of the knob device; the same principle exactly is involved whether one knob device and dog is used in 70 the construction of a lock, or whether several as for instance three, shown in Figs. 5 to 7, are used; it is entirely optional to the constructor which embodiment is employed under the scope of the appended claims. 75

It is to be understood that the elongated pockets 6, Fig. 3, are produced by scraping out enough metal, from the inner surface of the casing 1, to allow the dogs to ride over the ends of the knobs. 80

The auxiliary knob device comprises knob 35, having stem 36 extending into an annular casing 37; between the inner end of casing 37 and a portion of the plate 2 is positioned a coil spring 38 that presses inwardly on the 85 casing 37 for normally holding its inner end in the aperture 39 formed in the shackle 8. The object of this auxiliary knob device is to hold the shackle in its innermost position or shut, while the combination is being set. 90 By pulling outward on the auxiliary knob device, it will clear at its inner end the shackle, when the shackle is permitted to be moved outwardly to an unlocked or open position. 95

While I have described the preferred embodiment of my invention, and have illustrated the same in the accompanying drawings, certain minor changes or alterations may appear to one skilled in the art to which this invention relates, during the extensive manufacture of the same, and, I, therefore, reserve the right to make such alterations or changes as shall fairly fall within the scope of the appended claims. 100

What I claim is:

1. In a combination lock, the combination of a casing provided with a knob device, a shackle slidably mounted in said casing, said shackle provided with a spring-pressed dog, 110 means formed upon said knob device for receiving and holding one end of the dog for retaining the shackle in a locked position within the casing, and a spring in the casing and pressing against a portion of the shackle 115 for forcing the shackle outwardly when the knob device is operated for releasing the dog.

2. In a combination lock, the combination of a casing provided with a primary knob device, a shackle slidably mounted in said casing, said shackle provided with a dog co-operating with the knob device for locking the shackle within the casing, an auxiliary knob device upon the casing and engaging and entering a portion of the shackle, said auxiliary knob device comprising a knob having a stem, a casing mounted upon said stem, a spring interposed between a portion of the shackle and the inner end of the last-mentioned casing for holding the last-men- 130

tioned casing in engagement with the shackle, but permitting the knob to be drawn outwardly for releasing the shackle, and means for forcing the shackle outwardly 5 upon the casing when the primary knob device is operated for releasing the dog.

3. In a combination lock, the combination of a casing, said casing provided with an elongated pocket cut out of its inner face, a shackle in said casing, a dog pivotally mounted on the shackle and registering with the elongated pocket, a plate on said casing, a knob device rotatably mounted on the plate opposite to said elongated pocket in the casing, said knob device adapted to receive one 10 end of the dog for locking the shackle within the casing, and means for forcing the shackle outwardly when the knob device is operated for releasing the dog.

20 4. In a combination lock, the combination of a casing, a slidable shackle mounted in said casing, said shackle provided with an elongated aperture and with recesses at opposite sides of said aperture, a dog pivotally 25 mounted in said aperture, said dog including a body having at one end oppositely-extending arms, said arms seated in the recesses of the shackle, a spring mounted in the shackle and bearing against the body of the dog for 30 holding one end of the dog in an extended position, a plate or cover for said casing, and a knob device carried by the plate and co-operating with said dog for engaging the extended end and normally holding the 35 shackle in a closed position within the casing.

5. In a combination lock, the combination of a casing, a slidable shackle in said casing, a plate or cover on said casing, a knob device 40 rotatably mounted on said plate, said knob device provided at its inner end with a rim having a large slot and a plurality of small slots, a dog pivotally mounted on said shackle and having a body terminating at 45 its upper or outer end in a tooth, and said tooth adapted to pass through the small slots of the rim and the body of the dog adapted to pass through the large slot of the rim, whereby when the extended or 50 outer end of the dog is within the rim of the knob device, the shackle will be locked or retained within the casing.

6. In a combination lock, the combination of a casing, a slidable shackle within said 55 casing, a plate on said casing, a knob device on said plate, said shackle provided with a pivoted dog, and a bent or angular spring having its base seated in the shackle and having an extended end pressing 60 against a portion of the dog for holding the dog normally in an extended position at one side of the shackle for engaging said knob device whereby the knob device may retain the shackle in its innermost or locked position 65 within the casing.

7. In a combination lock, the combination of a casing, a slidable shackle in said casing, said casing provided with a rotatable knob device, a dog provided with a body and with oppositely-extending arms pivotally 70 mounted upon the shackle and adapted to extend through the same, a spring bearing against the back of the dog and having its base seated in the shackle, and said dog adapted to engage and enter a portion of 75 the knob device for normally holding the shackle in a closed position within the casing.

8. In a combination lock, the combination with a casing, of a shackle slidably mounted 80 in said casing, a knob device carried by the casing and co-operating with the shackle, said shackle provided with an elongated aperture and with arm recesses at opposite sides of the aperture and with a spring-receiving recess, a dog having a curved body and oppositely-extending arms, said arms positioned in the arm recesses, a spring having an outer free end pressing against the curved body of the dog and having edges 90 positioned in the spring recess of the shackle, and said knob device normally engaging and holding the dog for retaining the shackle in its innermost or closed position within the casing. 95

9. In a combination lock, the combination with a casing, of a shackle slidably mounted in said casing, a plate on said casing, a knob device rotatably mounted on said plate, said knob device including a rim at its inner end, 100 said rim having a large slot and a plurality of smaller slots, a ring rotatably mounted upon said rim, said ring provided with a large slot adapted to register with the large slot of the rim, said ring provided with 105 shoulders at opposite sides of its large slot, said rim provided with a bent-over portion or lug adapted to engage either of the shoulders of the ring for rotating the ring, a spring carried by the plate and engaging 110 the outer surface of the ring for retarding its rotary movement and also holding the ring upon the rim, and means on the shackle for co-operating with the rim and ring for retaining the shackle in a locked position 115 within the casing.

10. In a combination lock, the combination with a casing, of a shackle slidably mounted in said casing, a plate on said casing, said plate provided with a rotatable 120 knob device, said knob device including a rim, a ring on said rim, means acting as a brake and also as a securing means for said ring, means on the rim and ring for rotating the ring during a part of a revolution 125 of the rim, and means on the shackle co-operating with the rim and ring for normally retaining the shackle in a locked position within the casing.

11. In a combination lock, the combina- 130

tion of a casing, of a shackle in said casing, a plate on said casing, a knob device carried by the plate, said knob device including a dog-receiving means, a spring-held split ring on said dog-receiving means, means on the ring and on the dog-receiving means for moving the ring when the dog-receiving means is operated, and a dog on

said shackle and coöperating with said dog-receiving means and ring for holding the shackle normally in a locked position within the casing.

In testimony whereof I hereunto affix my signature.

FRANCIS C. VARTULLI
